(57) **CLAIM**

The ornamental design for a display screen or portion thereof with animated graphical user interface, as shown and described.

DESCRIPTION

FIG. 1 is a front view of a display screen or portion thereof with animated graphical user interface, showing a first image in a sequence showing our new design;

FIG. 2 is a front view of a second image thereof;

FIG. 3 is a front, view of a third image thereof;

FIG. 4 is a front view of a fourth image thereof;

FIG. 5 is a front view of a fifth image thereof;

FIG. 6 is a front view of a first image of a second embodiment thereof;

FIG. 7 is a front view of a second image thereof;

FIG. 8 is a front view of a third image thereof; and,

FIG. 9 is a front view of a fourth image thereof.

The appearance of the image transitions sequentially between the images shown in FIGS. 1 to 5 and FIGS. 6 to 9, respectively. The process or period in which an image transitions to another forms no part of the claimed design.

The broken lines represent portions of the animated graphical user interface, including graphical elements and text showing brand names, and form no part of the claimed design.
